UNITED STATES PATENT OFFICE

116,742

DESIGN FOR AN ATOMIZER

Frederick R. Hoch, Norton, Mass., assignor to
T. J. Holmes Co., Inc., Chartley, Mass., a cor-
poration of Massachusetts

Application June 23, 1939, Serial No. 85,646

Term of patent 3½ years

To all whom it may concern:

Be it known that I, Frederick R. Hoch, a citizen of the United States, residing in Norton, in the county of Bristol and State of Massachusetts, have invented a new, original, and ornamental Design for an Atomizer, of which the following is a specification, reference being had to the accompanying drawing, forming a part thereof.

In the drawing,

Fig. 1 is a plan view of an atomizer showing my new design;

Fig. 2 is a front elevational view of the atomizer shown in Fig. 1;

Fig. 3 is a side elevational view at right angles to the plane of Fig. 2.

The essential features of my design reside in the parts shown in solid lines, the side of the atomizer opposite to that shown in Fig. 2 being substantially identical in appearance with Fig. 2.

I claim:

The ornamental design for an atomizer, as shown and described.

FREDERICK R. HOCH.
